UNITED STATES PATENT OFFICE.

FRANK COATES, OF CLEADON, ENGLAND, ASSIGNOR TO A. REYROLLE & COMPANY LIMITED, OF HEBBURN-ON-TYNE, ENGLAND, A COMPANY OF GREAT BRITAIN.

ELECTRICAL SWITCH GEAR.

Application filed March 12, 1926, Serial No. 94,303, and in Great Britain May 19, 1925.

This invention relates to electrical switch-gear of the armoured draw-out type. With such switchgear, more especially when used for automatic substation work, it is often necessary to provide a number of auxiliary switches to be actuated from the operating mechanism of the main oil switch. The usual practice hitherto has been to mount such auxiliary switches in boxes carried on the main switch and to connect their actuating mechanisms directly with the main switch operating mechanism. This arrangement necessitates the provision of a large number of plug and socket connections, which engage with one another when the draw-out portion of the switch gear is moved into its operative position and which all have to be properly aligned.

The present invention has for its object to avoid the necessity of providing and aligning a large number of plugs, and to this end according to the invention the auxiliary switches are mounted on the fixed portion of the switchgear together with actuating mechanism therefor, and means are provided whereby when the draw-out portion of the switchgear is in its closed position the operation of the main switch contacts is caused to actuate also the auxiliary switches.

The actuating mechanism for the auxiliary switches may be operated mechanically or electromagnetically from the operating mechanism for the main switch. In the former case the actuating mechanism for the auxiliary switches is connected to the main switch operating mechanism through a coupling which is brought into engagement when the draw-out portion of the switch-gear is moved into its closed position. In the latter case the electromagnet or electromagnets operating the auxiliary switch actuating mechanism are controlled by a single auxiliary switch directly actuated by the main switch operating mechanism.

The invention may be carried into practice in various ways but two alternative preferred constructions according thereto are illustrated by way of example in the accompanying drawings, in which

Figures 1 and 2 show respectively front

and side elevations of one construction employing mechanical operation,

Figures 3 and 4 show similar views of a construction employing electromagnetic operation, and

Figure 5 is a diagram showing the electrical circuits in the construction of Figures 3 and 4.

In the construction of Figures 1 and 2, the draw-out portion A of the switchgear carries as is usual the oil tank A¹ containing the main switch contacts indicated at A², and in the example illustrated is mounted to slide on guides B¹ carried by the fixed portion B of the switchgear. The main switch contacts are operated by suitable mechanism from a handle A³ and part of this operating mechanism is indicated at A⁴. A link C is connected at one end to one member of this operating mechanism and is pivoted at its other end to one arm C¹ of a two-armed lever. The other arm C² of this lever has a pin-and-slot connection with a rod D, which can slide longitudinally in guides D¹ (carried on the draw-out portion A of the gear) and has inclined end face D².

In the drawing the parts are shown in the closed position of the main switch, and in this position the inclined end-face D² of the rod D engages with a roller E carried by a plunger E¹, which can slide in a cylinder E² mounted on the fixed portion B of the gear. This plunger E¹ is normally pressed into its lowermost position by means of a spring E³, and is raised into the position shown in the drawings by the movement of the rod D. The plunger E¹ has pivoted to it one end of a link F, whose other end operates a crank arm F¹ mounted on a shaft carrying the movable contact members F² of the auxiliary switches.

The auxiliary switches are conveniently carried within a box F³ which is mounted in a suitable position on the framework of the fixed portion B of the gear, such for example as in front of the frame either above (as shown) or below the draw-out portion, or at the back or side of the frame. Provision may be made, if desired, for a time relay in the operation of some or all of the auxiliary switches.

In this construction when the main switch

- contacts A^2 are opened, the rod D is withdrawn and the spring E^3 causes the roller E to ride down the inclined face D^2 of the rod and thereby to open the auxiliary switches.
- 5 Removal of the draw-out portion of the gear pulls the end of the rod D away from the roller E . When the draw-out portion of the gear is pushed back into its closed position, the end of the rod D will be brought up
- 10 against the roller E but will not act to raise the roller and the plunger until the main switch mechanism is operated.

Figures 3 and 4 show an alternative arrangement in which the auxiliary switches are operated electromagnetically when the main switch mechanism is operated. In this construction the auxiliary switches are again mounted in a box G carried by the fixed portion of the gear indicated at G^1 . These switches are in this case, however, actuated through a lever mechanism by means of two electromagnets H H^1 mounted for example on top of the auxiliary switch box G .

The draw-out portion of the gear is not shown in the drawings, but it is to be understood that it is constructed in the usual manner and that it carries an auxiliary switch which is directly actuated by the main switch operating mechanism. The connections for this auxiliary switch are taken through a single three-way plug, which is closed when the draw-out portion of the gear occupies its closed position. In the diagram of Figure 5, the main switch is indicated at J and this auxiliary switch at J^1 , and it will be seen that the auxiliary switch J^1 acts to determine which of the operating coils H H^1 of the electromagnets is in circuit. The circuits to these coils also contain two of the auxiliary switches G^2 G^3 contained in the switch box G . These two switches G^2 G^3 may be combined together to form a single two-way switch, if desired.

Returning to Figures 3 and 4, it will be seen that the armatures of the electromagnets H and H^1 are connected respectively to cranks K K^1 on a shaft K^2 , the arrangement being such that energization of one coil will act to rotate the shaft in a direction opposite to that due to energization of the other coil. A crank L on the shaft K^2 carries a pin L^1 engaging in a slot L^2 in a lever arm L^3 rotatably mounted on the shaft M which carries the movable contact members of the auxiliary switches. A second lever arm N , also rotatably mounted on the shaft M , engages with the lever arm L^3 through a claw clutch N^1 , which allows a small amount of free motion. The second lever arm N is controlled by means of a compression spring O carried on an arm O^1 pivoted at O^2 to a bracket O^3 on the wall of the switch box G . On the side remote from the claw clutch N^1 the lever arm N engages through a second claw clutch N^2 with a member M^1 carried on

the shaft M , this second claw clutch also allowing a small amount of free motion.

As shown in the drawings the parts are in the positions occupied when the main switch is open, and in this position the auxiliary switch G^2 is closed and the switch G^3 is open. Since the auxiliary switch J^1 is in circuit with the coil H^1 and not with the coil H in this position, no current is supplied to either electromagnet. If now the main switch J is closed, the auxiliary switch J^1 moves over into circuit with the coil H and this coil is therefore energized. Its armature will act on the crank K to rotate the shaft K^2 , so that the lever arm L^3 will act through the claw clutch N^1 to rotate the lever arm N about the shaft M compressing the spring O . The second claw clutch N^2 is arranged to engage when the lever arm N has nearly come into line with the arm O^1 , i. e. 85 when the spring O is almost fully compressed. The continued movement of the lever arms therefore causes rotation of the shaft M and the auxiliary switches are operated, a snap action being obtained by the sudden release of the spring O when the centre line is passed (this sudden release being allowed by the free motion of the claw clutch N^1). The rotation of the shaft M causes the operation of the auxiliary switches including the switches G^2 and G^3 , and the opening of the switch G^2 deenergizes the coil H whilst the closing of the switch G^3 prepares the circuit to the coil H^1 , this circuit not being completed until the auxiliary switch J^1 100 is again moved over when the main switch J is opened. An exactly similar series of operations takes place when the main switch is opened as a result of which all the parts are brought back to the positions shown. It 105 will be noticed that the coil H is energized when the main switch is closed and is deenergized when the auxiliary switches operate, whilst the coil H^1 is energized when the main switch is opened and is deenergized again as soon as the auxiliary switches operate. The electro-magnets are thus always inoperative unless the auxiliary switches are actually being operated.

The actual arrangement of the auxiliary switches may vary according to requirements. Thus they may each have only a single set of contacts which is opened or closed when the main switch is closed and vice versa, or some or all of the auxiliary 120 switches may have two sets of contacts one of which is opened and the other closed when the main switch is closed. Again some of the switches may be early-acting (i. e. operated immediately or with only a 125 short time-delay after the main switch is operated), whilst some are late-acting or have a relatively long time-delay in their operation.

It is to be understood that the two alter- 130

native arrangements above described in detail have been given by way of example only, and that they may be modified in various ways without departing from the scope of the invention.

What I claim as my invention and desire to secure by Letters Patent is:—

1. In electric switchgear of the armoured draw-out type, the combination with the operating mechanism for the main switch contacts carried on the draw-out portion of the switchgear, of a number of auxiliary switches mounted on the fixed portion of the gear, actuating mechanism for such auxiliary switches also carried on the fixed portion of the gear, a coupling which is brought into engagement when the draw-out portion is moved into its closed position and is disengaged when the draw-out portion is withdrawn, and means whereby the operation of the main switch contacts causes power to be transmitted through the coupling, when engaged, for the actuation of the auxiliary switches.
2. In electric switchgear of the armoured draw-out type, the combination with the fixed and draw-out portions of the switchgear, of main switch contacts, operating mechanism for the main switch contacts, such contacts and their operating mechanism being carried on the draw-out portion of the gear, a plurality of auxiliary switches, actuating mechanism for the auxiliary switches, such switches and their actuating mechanism being carried on the fixed portion of the gear, two members mounted respectively on the fixed and draw-out portions of the gear and adapted to engage with one another when the draw-out portion is in its closed position, and means for transmitting power from the main switch operating mechanism through the two members when engaged to the auxiliary switch actuating mechanism whereby the operation of the main switch contacts is caused to actuate also the auxiliary switches.
3. In electric switchgear of the armoured draw-out type, the combination with the operating mechanism for the main switch contacts carried on the draw-out portion of the switchgear, of a number of auxiliary switches mounted on the fixed portion of the gear, actuating mechanism for such auxiliary switches also carried on the fixed portion of the gear, a coupling which is brought into engagement when the draw-out portion is moved into its closed position, and means whereby power for the actuation of the auxiliary switches is transmitted mechanically from the main switch operating mechanism through the coupling to the auxiliary switch actuating mechanism.
4. In electric switchgear of the armoured draw-out type, the combination with the operating mechanism for the main switch contacts carried on the draw-out portion of the switchgear, of a number of auxiliary switches mounted on the fixed portion of the gear, a shaft carrying the movable contact members of the auxiliary switches, a driven member carried on the fixed portion of the gear and operatively connected to the contact-carrying shaft, a driving member carried by the draw-out portion of the gear and operatively connected to the main switch operating mechanism, and means whereby power for the actuation of the auxiliary switches is transmitted from the driving member to the driven member when the draw-out portion of the gear is in its closed position.
5. In electric switchgear of the armoured draw-out type, the combination with the operating mechanism for the main switch contacts carried on the draw-out portion of the switchgear, of a number of auxiliary switches mounted on the fixed portion of the gear, a shaft carrying the movable contact members of the auxiliary switches, a driven member carried on the fixed portion of the gear and operatively connected to the contact-carrying shaft, a driving member carried by the draw-out portion of the gear and so arranged as to brought into operative engagement with the driven member when the draw-out portion is moved into its closed position, and means for imparting movement to the driving member when the main switch contacts are operated, such movement being transmitted through the driven member for the actuation of the auxiliary switches.
6. In electric switchgear of the armoured draw-out type, the combination with the operating mechanism for the main switch contacts carried on the draw-out portion of the switchgear, of a number of auxiliary switches mounted on the fixed portion of the gear, a shaft carrying the movable contact members of the auxiliary switches, a longitudinally movable rod having an inclined end-face, a driven member operatively connected to the contact-carrying shaft and adapted to engage with the inclined end-face of the rod when the draw-out portion of the gear is in its closed position, and means associated with the main switch operating mechanism for moving the rod longitudinally when the main switch contacts are operated, such movement being transmitted through the driven member for the actuation of the auxiliary switches.
7. In electric switchgear of the armoured draw-out type, the combination with the operating mechanism for the main switch contacts carried on the draw-out portion of the switchgear, of a number of auxiliary switches mounted on the fixed portion of the gear, a shaft carrying the movable contact members of the auxiliary switches, a longi-

tudinally movable rod carried on the draw-out portion of the gear and having an inclined end-face, a roller so disposed on the fixed portion of the gear as to engage with the inclined end-face of the rod when the draw-out portion of the gear is in its closed position, a plunger carrying the roller, a spring acting on the plunger and tending to hold the roller in engagement with the in-

clined end-face, means whereby movement of the plunger is caused to rock the contact-carrying shaft, and means associated with the main switch operating mechanism for moving the rod longitudinally when the main switch contacts are operated. 10 15

In testimony whereof I have signed my name to this specification.

FRANK COATES.
